Primary Examiner — Susan B Hattan*Assistant Examiner* — Vy Koenig(74) *Attorney, Agent, or Firm* — Fishman Stewart Yamaguchi PLLC(57) **CLAIM**

The ornamental design for a camera holder, as shown and described.

DESCRIPTION

FIG. 1 is a front, top, right perspective view of a camera holder showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict unclaimed portions of the camera holder that form no part of the claimed design.
